ELECTRODE HOLDER

William R. Stewart, Sterling, Ill., assignor to
Northwestern Steel and Wire Company, Sterling, Ill., a corporation of Illinois

Application May 7, 1942, Serial No. 442,014

8 Claims.

(Cl. 13—14)

This invention relates to a holder or clamp especially adapted to support a member while placing the member in good electrical contact therewith.

Specifically the invention relates to electrode holders useful on electric melting furnaces.

While the invention will hereinafter be specifically described in connection with an electric furnace for the melting and refining of steel it should be understood that the holders of this invention are adapted for general usage and that the invention includes within its scope all uses of the holders.

In electric metal melting furnaces electrodes such as carbon rods depend from supports into the body or hearth of the furnace. These electrodes must, from time to time, be adjusted relative to their supports in order that progressive feeding of the electrodes into the hearth portion of the furnace can continue as the electrodes are used up. It is quite customary to add electrode lengths to the tops of partially used electrodes so that the feeding of the electrodes into the hearth as the same burn up may continue without wastage of electrode material.

Since the electrodes must receive electrical current it is highly desirable that the supporting members or holders for the electrodes have good electrical contact therewith. This electrical contact should not be rendered inefficient by heating of the holders such as normally occurs during operation of an electric furnace.

The present invention now provides electrode holders which can receive electric current therethrough for energizing the electrodes gripped thereby. The holders of this invention have appreciable area contact with the electrodes so as to establish excellent electrical conductivity between the electrodes and holders.

The holders of this invention can be quickly clamped around electrodes or loosened from electrodes as desired. As a result of this feature the electrodes can readily be adjusted relative to the holders.

A special feature of this invention includes the provision of coolant passageways in the holders so that cooling material may be circulated therethrough to prevent excessive heating of the holders.

Another feature of the invention resides in a simplified mounting arrangement for the electrode holders wherein the same are placed in insulated relation to the melting furnace so that they can be heavily charged with electrical cur-

rent without danger of establishing short circuits.

Another feature of this invention resides in the utilization of hollow tubes to conduct coolant and electrical current to the holders. The coolant will pass through the tubes while the electrical current will be conducted by the tubes.

It is, then, an object of the invention to provide a holder or clamp capable of being quickly adjusted for gripping a member and for loosening the gripped member.

A still further object of the invention is to provide a holder capable of establishing good electrical contact with a held member over an appreciable area of the member.

A still further object of the invention is to provide an electrode holder especially adapted for use on electric melting furnaces which is not rendered inefficient by heat.

20 A still further and specific object of this invention is to provide an electrode holder for electric furnaces which is capable of supporting an electrode in good electrical contact therewith and which is adapted to be cooled during use by flow of a coolant therethrough.

Another specific object of the invention is to provide an electrode holder for electric melting furnaces which will not warp during use and which can be readily loosened from an electrode held thereby.

Other and further objects of the invention will be apparent to those skilled in the art from the following detailed description of the annexed sheets of drawings which, by way of preferred example, illustrate one embodiment of the invention.

On the drawings:

Figure 1 is a top plan view of an electric melting furnace equipped with electrode holders according to this invention.

Figure 2 is a side elevational view of the melting furnace and electrode holders illustrated in Figure 1 and also showing the manner in which the electrode holders can be raised or lowered relative to the body portion of the furnace.

Figure 3 is an enlarged fragmentary plan view of one of the electrode holders with parts cut away and shown in horizontal cross section.

Figure 4 is a fragmentary side elevational view of the electrode holder illustrating the same in gripping relation to an electrode.

Figure 5 is a front end elevational view along the line V—V of Figure 4.

55 Figure 6 is a vertical cross-sectional view

along the line VI—VI of Figure 4 with parts in elevation.

Figure 7 is an enlarged vertical cross-sectional view, with parts in elevation, taken along the line VII—VII of Fig. 2.

As shown on the drawings:

In Figures 1 and 2 the reference numeral 10 designates generally an electric furnace such as a Heroult furnace for the melting and refining of metals such as steel. The furnace 10 includes a body portion 11 defining a hearth for the materials to be charged therein. A horizontally swingable cover 12 is provided for the body 11 and this cover may have an extension 12a for supporting three vertical columns 13. A carriage 14 is movably mounted on each column 13 so that it can be raised and lowered relative to the cover of the furnace. Rollers 14a on the carriage 14 can, for example, roll on opposite rounded end walls of the column. The carriage structure and the manner of supporting the same relative to the furnace can of course be modified widely and it is merely intended to show a movable type of mounting for better illustrating the electrode holder of this invention.

As shown in Figure 2, the tops of the columns 13 can have supports such as 15 thereon carrying pulleys 16 over which a cable or other lifting device 17 can be passed. The cable 17 is also directed around a pulley 18 carried by the carriage structure 14. One end of the cable can be anchored to the support 15 as at 17a for example. Actuation of a cable will thereby raise and lower a carriage 14 on its supporting column 13.

Each carriage 14 has a laterally projecting tubular mounting part or clamping sleeve 19. As best shown in Figure 7, each tubular mounting part 19 is composed of semi-cylindrical mating sections 19a, 19a having outturned flanges 19b, 19b for receiving bolts 20 therethrough to draw the half-sections together in clamping relation around an inserted member.

A rigid metal tube 21 is inserted in each member 19 and is surrounded by a sleeve 22 of mica or other electrical insulation so that the tube 21 will be in insulated relation to its mounting support 19. The mounting support 19 can be clamped tightly around the mica sleeve 22 so that the tube 21 will be fixedly carried by the mounting member 19.

Each tube 21 projects longitudinally beyond the end of its mounting member 19 and has its projecting free end vertically slotted as at 21a and 21b to receive metal plates 23. As shown in Figure 7, the slots 21a are in vertical alignment on one side of the tube 21 while the slots 21b are in vertical alignment on the other side of the tube 21 so that the plates 23 will be mounted in spaced vertical relation from each other. The plates can be welded to the tube 21 as at 24. It should be understood, of course, that any other suitable manner of securing the plates to the tube can be used. The slots project inwardly from the free end of the tube 21 for an appreciable distance as shown in Figures 3 and 4 so that an appreciable length of each plate 23 can be disposed in a slot.

The plates 23 project beyond the free end of the tube 21 and receive therebetween the shank 25a of the electrode holder 25. Conductor plates 26 are disposed between each plate 23 and the shank 25a. Bolts 27 extend through the plates 23, the conductor plates 26, and the shank 25a and have heads 27a on one of the ends thereof and

5 nuts 27b threaded on the other ends thereof so that the assembly can be tightly clamped and rigidly affixed together. Each conductor plate 26 is joined in good electrical contact with a hollow conductor tube 28. The plates 26 can be brazed, welded, or otherwise secured to the conductor tube 28.

As shown in Figures 1 and 2, each carriage assembly has a pair of the conductor tubes 28 thereon extending from the conductor plates 26 rearwardly in spaced relation above the tube 21 and the mounting sleeve 19. The tubes are then bowed outwardly to clear the sides of the carriage 14 and are affixed to the carriage 14 by means of brackets 29 lined with a sleeve of mica or other insulating material 30 so that the tubes will be in insulated relation to the carriage assembly and will have good electrical contact with the electrode 25 through the conductor plates 26. The mica sleeve 22 of the assembly will prevent flow of electric current to the carriage from the plates 23 and tubes 28.

The rear ends of the tubes 28 have current conducting clamps 31 thereon to which are connected power lines 32. Current is thus supplied to the tubes 28.

Coolant conduits 33 are coupled to the rear ends of the tubes 28 for flow of a cooling fluid through the tubes. These conduits 33 can be made of insulation material or can be connected in insulated relation with the tubes 28. The inner ends of the tubes 28 are closed as by means of caps 28a or other closure means (Fig. 4).

The electrode holders 25 are thus in fully insulated relation to the supporting structure and receive current from the power lines 32 through the tubes 28. These electrode holders 25 each clamp an electrode E which extends through the cover 12 of the furnace into the body portion 11 of the furnace. Three electrodes and three electrode holders 25 are shown in Figures 1 and 2.

Since the electrodes E are used up during the melting operation, it is necessary to gradually feed the electrodes into the body 11 of the furnace, and, for this purpose, the carriages 14 can be lowered as desired. When the electrode holders 25, however, approach the cover 12 of the furnace, it is necessary to add lengths to the electrode E, and, for this purpose, additional electrode material is fastened to the upper ends of the partially used electrodes and the electrode holders must be loosened so that the added lengths of electrode material can be fed into the furnace. It has heretofore been quite a problem to loosen the electrode holders from the gripped electrodes since the same would become fused to the holders. Another defect in previously known electrode holders resides in the fact that the same will become warped due to heat from the furnace and will expand so as to be out of good electrical contact with the electrode as well as permitting the electrode to slip. Frequently the electrode holders became so badly warped that they were unfit for use.

In accordance with this invention the electrode holders can be maintained in a cool condition even though they are subjected to intense heat from the furnace. Also in accordance with this invention, the holders can be readily loosened from the electrodes as well as readily tightened around the electrodes in good electrical contact therewith.

The electrode holder 25, as shown in Figures 3 and 4, has the shank portion 25a between the conductor plates 26. A pair of clamping jaws 25b

extend from the shank portion 25a around the electrode E. While these clamping jaws 25b are shown as each having a semi-cylindrical contour it should be understood that they can have any desired shape depending upon the shape of the member to be gripped thereby.

The shank portion 25a is preferably hollowed out as at 25c at the transition point between the shank and clamping jaws so as to facilitate springing the jaws toward and away from each other.

Each jaw 25b preferably has extended top and bottom sections 25d to increase the area contact between the electrode E and the clamping jaws. These sections or extensions, of course, can be eliminated if desired.

As best shown in Figures 3, 4 and 5, the clamping jaws 25b terminate in spaced opposed ears or lugs 25e extending outwardly from the free ends of the jaws. The lugs 25e have recesses 25f extending inwardly from the free ends thereof. These recesses of the respective lugs are in alignment with each other and receive square or rectangular internally threaded bushings 35 in non-rotatable relation therein. Each bushing 35 has flanges 35a on opposite ends thereof for retaining the bushings against endwise movement in the recesses. These flanges engage the inner and outer walls of the lugs respectively.

The flanges engaging the outer walls of the lugs may be heavier than the flanges engaging the inner walls since they are intended to carry appreciable loads when the jaws are tightly clamped around the electrode. The inner flanges 35a can be of lighter construction since they are primarily expanding means for loosening the clamping jaws from a clamped electrode.

The aligned sets of bushings 35 in the recesses 20 are adapted to receive the oppositely threaded ends of double shanked bolts 36. The bolts 36 have turning heads or knobs 36a disposed between the lugs 25e for engagement with a wrench to rotate the bolts for expansion and contraction of the clamping jaws 25b.

In order to protect the bolts, one of the clamping lugs 25e can have a lipped portion or flange 25g extending from the upper end thereof over the space between the lugs while a similar lip or flange can be formed on the lower end of the other lug to extend across this space. The bolts are thus extended through a chamber defined by the lugs 25e and the top and bottom lips 25g.

Rotation of the bolts in one direction will move the bushings 35 away from each other thereby causing the inner flanges 35a on these bushings to spread the lugs apart and thereby spread the clamping jaws. Reverse rotation of the bolts will draw the bushings 35 toward each other and cause the outer flanges on these bushings to draw the lugs 25e toward each other. This, of course, will draw the clamping jaws together for gripping the electrodes.

The clamping jaws will flex mostly at the transition area adjacent the shank 25a since the hollow portion or cut-out portion 25c renders the assembly somewhat flexible at this area. The jaws, however, will be contracted uniformly around the electrodes so as to exert uniform gripping pressure thereagainst over an appreciable area thereof.

The electrode holder 25 is preferably formed of cast metal having good electrical conducting capacity coupled with heat resistivity. A suitable metal for this purpose is "Mallory Metal No. 333" sold by T. R. Mallory & Co. Inc. This

is a tungsten alloy having especially good electrical conductivity coupled with heat resistivity.

This metal is cast around tubes or pipes 40 which are bent in a serpentine path extending through the shank area, the clamping jaw area and into the lug areas of the electrodes.

The pipe 40 can be coiled, for example, to enter the top wall of the electrode at the rear end of the shank and extend forwardly through the shank and one of the clamping jaws to the lug of this clamping jaw. The pipe can then be reversed on itself to pass back through the same clamping jaw to the rear end of the shank. Several such reverse bends of the pipe can be made to provide a serpentine passageway along one side of the electrode. As shown in Figure 6, the pipe can then extend to the other side of the shank at the rear bottom end thereof and be coiled in a similar manner to pass through the opposite clamping jaw and lug. The end of the pipe will then emerge out of the top wall of the shank adjacent the incoming end of the pipe. The ends of the pipe 40 can then be connected to tubes 41 and 42 respectively. The tube 41 extends into one of the conductor tubes 28 while the tube 42 extends into the other conductor tube 28. The tubes 41 and 42 can be brazed or welded or otherwise coupled to the tubes 28.

Coolant material can be introduced into the rear end of one tube 28 of each pair for flowing through the electrode contained coiled tube or pipe 40. The other tube 28 of each pair can receive the coolant from the electrode holder to discharge the same.

Obviously, of course, the electrode holder could be internally cored to provide a hollow passageway for flow of coolant therethrough. The casting of the electrode holder metal around a coiled pipe is a convenient method of forming the passageway.

Any suitable type of coolant can be used, such as water, for example. Since the coolant will flow in good heat exchange relation with all areas of the electrode holder, no portion of the holder will become overheated.

From the above descriptions it will be understood that this invention now provides an improved holder or clamp especially useful for clamping electrodes in electric melting furnace constructions. The holders of this invention are quickly clamped around a member to be held thereby and are quickly loosened from such a held member. The holders are mounted in a manner such that they have good electrical contact over extended areas with a source of electrical current as well as with the member gripped thereby. The holders can be internally passaged for receiving cooling fluid and are arranged so as to be readily mounted in insulated relation with a supporting structure such as an electric furnace carriage mounting.

The electrical current can be fed to the holders of this invention by means of hollow tubes which also convey coolant to and from the holders.

It will, of course, be understood that various details of the invention may be varied through a wide range without departing from the principles of this invention and it is, therefore, not the purpose to limit the patent granted hereon otherwise than necessitated by the scope of the appended claims.

I claim as my invention:

1. An electrode holder adapted for electric melting furnaces and the like having a carriage supporting column and a carriage ridable on said

column which comprises a clamping sleeve projecting from said carriage; a tube clamped in said sleeve in insulated relation therewith, said tube having a free end with inwardly projecting slots, spaced opposed plates secured in the slots of said tube, an electrode holder having a shank portion disposed between said plates, conductor plates interposed between said shank portion and said plates, means clamping said shank portion and said conductor plates between said plates, said electrode holder having coolant circulating passageways therein; a metal tube secured to each conductor plate for circulating current through said plate and electrode holder, means connecting the interior of each tube with the passages in said electrode holder, means mounting said tubes on said carriage in insulated relation therefrom; and means for connecting one of said tubes with a source of coolant for circulation through the said tube and through the electrode holder into the other tube for discharge therefrom.

2. An electrode mounting assembly for melting furnaces and the like comprising a carriage adapted to be mounted for vertical movement relative to a furnace, a rigid tube carried by said carriage in insulated relation therefrom, a pair of spaced opposed rigid plates affixed to said tube, an electrode holder having a shank portion disposed between said plates, conductor plates interposed between said plates and opposite sides of said shank portion, means clamping said conductor plates and shank portion between said plates, a pair of hollow metal tubes extending from said carriage to said conductor plates, insulation means maintaining said tubes in insulated relation to said carriage, means joining each tube with a conductor plate in good electrical contact therewith, said electrode holder having a coolant circulating passage therethrough, a conduit connecting one end of said passage with one of said tubes, a second conduit connecting the other end of said passage with the other of said tubes, means connecting said tubes with a source of electrical current, means connecting one of said tubes with a cooling medium, and means connecting the other of said tubes with a drain whereby said tubes will convey electrical current and coolant through said electrode holder in insulated relation with said carriage.

3. Electrode mounting means for electric furnaces and the like which comprises a vertically movable carriage, a metal tube extending from said carriage in insulated relation therefrom, a pair of plates projecting in spaced opposed relation from said tube, and an electrode holder having a shank portion clamped between said plates.

4. In an electrode holder assembly, mounting members including plate-like mounting means, a plate-like current conductor, means for supplying current to said conductor, an electrode

holder having a shank and electrode clamping jaws associated therewith, said shank being disposed in surface engagement with said conductor, means for securing said mounting means, said shank, and said conductor tightly in surface engagement to afford a mounting arm for said jaws, and means for supporting said arm on a furnace or the like.

5. An electrode holder comprising a holder having a shank portion and opposed clamping jaw portions integral with said shank portion, each jaw portion having a plurality of superimposed passageways therein extending into the shank portion and defining separate serpentine circulating paths through each jaw and each side of the shank portion beginning and terminating in the shank portion, said shank portion having a passageway joining the beginning of one path with the terminal end of the other path, a drain tube communicating with the terminal end of said one path, and a coolant feed tube communicating with the beginning of said other path whereby coolant will first be circulated through one clamping jaw and one side of the shank portion and thence through the other side of the shank portion and other clamping jaw.

6. Electrode mounting means for electric furnaces and the like which comprises a support, a metal tube extending from said support in insulated relation therefrom, a pair of spaced opposed metal plates projecting from said tube, and an electrode holder having a shank portion clamped between said plates.

7. Electrode mounting means for electric furnaces and the like which comprises a metal tube having spaced, parallel slots extending inwardly from one end thereof, a metal plate secured in each slot and projecting from said tube in spaced opposed relation, and an electrode holder having a shank portion clamped between said metal plates.

8. An electrode holder assembly comprising a pair of spaced opposed plates, an electrode holder having a shank extending between said plates, plate conductors between said shank and said plates, means securing said shank, plate conductors and opposed plates together to form a laminated block, a passaged conductor secured to each plate conductor, said electrode holder having fluid circulating passages therein, tubes connecting the electrode holder passages with the conductor passages, means for electrically energizing both passaged conductors to flow current through the conductor plates to the holder, means for feeding coolant through one passaged conductor into the holder, and means for draining fluid from the other passaged conductor to maintain circulation of coolant through the holder.

WILLIAM R. STEWART.
